SPRING REACTION NEUTRALIZER

Roderic M. Cross, Minneapolis, Minn., assignor to Grosvenor M. Cross, Newton Center, Mass.

Application July 7, 1928. Serial No. 291,016

9 Claims. (Cl. 267—8)

This invention relates to new and useful improvements in spring reaction neutralizers, and more particularly to such devices of the type adapted for use in connection with motor vehicle springs.

An object of the present invention is to provide a spring reaction neutralizer comprising a member adapted to be secured to the vehicle chassis, and a casing mounted for relative rotary movement upon said chassis and connected with the vehicle axle in a manner to cause the casing to be relatively rotated upon the member, when the vehicle spring or springs flex because of irregularities in the road-way, and means being provided in connection with said member and casing permitting freedom of movement of the casing in either direction from a normal position, but resisting the return movement of the casing; such resistance acting to oppose or neutralize that force of reaction which is the difference between the weight resting upon the spring and the total force stored within the spring.

A further object of the invention is to provide a spring reaction neutralizer comprising a member adapted to be secured to the vehicle chassis, and a casing mounted for relative movement upon said member and cooperating therewith to provide a fluid-tight chamber, said casing having a connection with the vehicle axle so that when the axle is moved relative to the chassis, the casing will partially rotate upon the member, and a cylinder, piston and suitable valve mechanisms within the above mentioned member adapted to control fluid circulation in the chamber, said parts being arranged to permit freedom of movement of the casing upon the member, when the vehicle spring is flexed in either direction from normal, but resisting the return movement of the spring to normal, the resisting forces neutralizing the reactive forces stored in the vehicle spring when flexed.

The particular object of the invention, therefore, is to provide an improved spring reaction neutralizer, more particularly adapted for use in connection with vehicle springs, to neutralize the reactive forces stored therein when flexed in either direction from normal. The present invention is an improvement over the structure shown in pending application, Serial No. 233,975, filed November 17, 1927, Patent No. 1,797,719, March 24, 1931, as a joint application by the inventor hereof and Grosvenor M. Cross.

Other objects of the invention will appear from the following description and accompanying

drawings and will be pointed out in the annexed claims. In the accompanying drawings, there has been disclosed a structure designed to carry out the various objects of the invention, but it is to be understood that the invention is not confined to the exact features shown as various changes may be made within the scope of the claims which follow.

In the accompanying drawings forming part of this specification:

Figure 1 is a view illustrating a portion of a motor vehicle with the invention applied thereto; Figure 2 is an enlarged sectional view on the line 2—2 of Figure 4, showing the parts in normal position;

Figure 3 is a similar view, showing a position assumed by the parts when the vehicle wheel strikes a bump in the road-way;

Figure 4 is a sectional plan view on the line 4—4 of Figure 2; and

Figure 5 is a vertical sectional view on the line 5—5 of Figure 2, showing the piston in elevation.

In the selected embodiment of the invention here shown, there is illustrated for purposes of disclosure, a portion of a motor vehicle comprising the chassis side beam 2 and front axle 3, connected with the chassis by means of a spring 4, here shown as being of the semi-elliptic type.

The invention comprises a member 5 having a cylindrical off-set portion 6, adapted to be secured to a support such as the side beam 2 of the vehicle chassis, by means of suitable bolts 7, as shown in Figure 5. The member 5 has an annular flange 8, the periphery of which is cylindrical and machined to rotatably receive a casing 9, open at one side and threaded at 11 to receive a cover plate 12, having a central bore adapted to receive the off-set portion 6 of the member 5. The packing plate 12 has an annular recess adapted to receive a suitable packing 13, retained therein by means of a packing nut 14, shown in Figure 5. The member 5 and casing 9, when assembled as above described, define a fluid-tight chamber 24, adapted to contain an inelastic fluid. (See Figures 2 and 3.)

A cylinder 15, having lugs 16 thereon, is mounted within the casing 9 and secured thereto by means of suitable bolts as shown in Figures 2, 3, and 4. The upper end of the cylinder 15 is threaded to receive a flanged cap 17 having an air vent 18 therein to permit escape of the entrapped air.

A hollow plunger 19 is movably mounted within the cylinder 15 and has a head 21 provided at its lower end, adapted to ride upon a cam surface 110

22, preferably integrally formed with the annular flange 8 of the member 5, as shown in Figures 2 and 3. Inclined intake apertures 23 are provided in the head 21 and establish communication between the fluid chamber 24 and the interior of the plunger 19.

An intake valve 25 is mounted in a valve seat member 26, provided at the lower end of the plunger 19 adjacent to the apertures 23. The member 26 has a guide adapted to receive the valve stem 27. A compression spring 28 has one end seated against the valve seat member 26 and its opposite end against a pin 29, mounted in the lower end of the valve stem 27. This spring normally retains the valve 25 in closed position as shown in Figure 2. The valve seat member 26 is also provided with fluid-circulating passages 31, shown in dotted lines in Figures 2 and 3.

The plunger head 21 is provided with projections 20 received in notches 30 provided in the lower edge of the cylinder wall 15. These projections and notches co-operate to prevent relative rotation of the plunger with respect to the cylinder. The plunger head 21 is forcibly held in contact with the cam surface 22 by means of a compression spring 40, mounted within the plunger and having one end seated against the cap 17 and its opposite end against a spacing member 50 engaged with the valve seat member 26. The spacing member 50 has a central opening permitting fluid flow therethrough.

Means are provided for controlling the circulation of fluid through the hollow plunger 19 and cylinder 15, when the neutralizer is actuated by relative movement of the vehicle axle, with respect to the chassis 2. Such means is shown in Figures 2, 3, and 4, and comprises a valve seat member 32 having a threaded extension 33 received in a threaded socket 34, provided at the upper end of the cylinder 15, as shown in Figure 2. The extension 33 has a bore 35 establishing communication between the interior of the cylinder and a bore 36, provided in the member 32. A fluid control valve 37, having a stem 38 is movably mounted in the member 32 and is normally retained in valve-closing position by means of a compression spring 39, having one end seated against the valve head 37 and its upper end against the bottom of a socket 41, provided in an adjusting screw 42 mounted in the upright wall of the casing 9. (See Figure 4.) A lock nut 43 is received in threaded engagement with the adjusting nut 42 and provides means for locking the latter in adjusted positions in the wall of the casing 9. The tension of the spring 39 controls the discharge of fluid from the cylinder 15 and plunger 19, when the casing returns from the position shown in Figure 3 to its normal position, shown in Figure 2. The casing 9 has an arm 44 on one side thereof provided with a suitable ball 45 to which one end of a connecting rod 46 is connected, the opposite end of which is similarly connected to the vehicle axle 3, as shown in Figure 1.

The valve stem 38 of the valve 37 has a reduced portion 47, thus providing an annular shoulder 48, the effective area of which is relatively less than the effective area of the valve head 37, as shown in Figure 4. Thus, when the pressure fluid is forced into the bore 36, it will act against the shoulder 48, thus partially balancing the valve 37. The valve, however, will open against the tension of the spring 39 because of the increased effective area of the bottom of the valve head 37.

The casing 9 is provided at its upper end with

a filler pipe 49 and plug 51, through which a suitable fluid may be introduced into the chamber 24. A drain plug 52 is provided at the bottom of the casing, through which the fluid may be drained from the chamber.

In the operation of this novel spring reaction neutralizer, the parts will normally be positioned as shown in Figure 2, with the valves 25 and 37 in closed position. When the vehicle wheel 53 encounters a bump in the road way, the axle 3 will be moved upwardly relative to the chassis frame 2, thereby relatively rotating the casing 9 upon the member 5, because of its connection with the axle by means of the connection 46. Such movement of the casing 9 upon the member 5, will cause the cylinder and piston to partially rotate within the chamber 24, as a result of these parts being connected with the casing 9, as previously described.

During such movement of the cylinder and plunger, the latter will be forced downwardly within the cylinder by the action of the spring 40, thereby causing the intake valve 25 to open against the tension of the spring 28, and permitting additional fluid to enter the plunger and 100 cylinder, as indicated by the arrows in Figure 3. Return movement of the vehicle spring 4 from an abnormal or flexed position, to its normal position, will be resisted by the action of the control valve 37, which tends to remain in closed position because of the spring 39 acting thereagainst.

The valve 37 therefore tends to prevent the discharge of fluid from the cylinder, but, as the vehicle spring 4 returns to normal position, the plunger head 21 will be moved upwardly, because 110 of its engagement with the cam surface 22, resulting in the intake valve 25 closing and the control valve 37 being open to permit the escape of the additional fluid from the cylinder and plunger. Because of the control valve 37 being partially balanced, as hereinbefore stated, the spring 39 may be of relatively light material. Adjustment of the adjusting screw 42 will control the action of the valve 37, and provides means for varying the resistive forces acting to prevent the 120 casing 9 to return from the position shown in Figure 3, to its normal position, shown in Figure 2, so that such forces may be adjusted to substantially neutralize the reactive forces stored in the vehicle spring when in a position other than normal. Conversely, when the vehicle wheel drops into a depression in the road surface, the casing 9 will be rotated in the opposite direction from normal, causing the plunger head to engage the cam surface upon the opposite side of the vertical. The return to normal position of the casing 9, and therefore the vehicle axle 3, will be controlled by the action of the control valve 37 in a manner similar to that above described with reference to Figure 3.

The novel spring reaction neutralizer featured in this invention comprises few parts and is comparatively light in weight. The large surface between the annular flange of the casing 9 and the annular flange 8 of the member 5, provides a large bearing area or surface which is thoroughly lubricated because of suitable grooves 54 provided in the annular flange 8 of the member 5, and further, because of the chamber 24 being substantially filled with a suitable non-elastic lubricating fluid. The relatively small area of the mounting surface and general shape of the neutralizer, also eliminates much interference and difficulty in mounting. It will also be noted that no roller or ball bearings are used in the construc- 145 150

tion thereof, thereby greatly reducing the cost of manufacture. The novel design of the partially balanced control valve 37 facilitates adjustment of the device and also permits the use of lighter parts. It will also be noted that the device provides its own oil chamber, no auxiliary oil reservoirs being necessary.

I claim as my invention:

1. A spring reaction neutralizer comprising a member adapted to be secured to a vehicle chassis, a casing mounted on said member and having an arm adapted to be connected to the vehicle axle, said member and casing cooperating to define an oil tight chamber, an inelastic fluid in the chamber, a cylinder secured to the casing within said chamber, a spring-actuated fluid control valve at one end of the cylinder, a hollow plunger movable in the cylinder and having an intake valve at one end thereof, and means for actuating said plunger, when said casing is relatively rotated upon the member, said valves controlling the flow of fluid through said cylinder and plunger in a manner to permit freedom of movement of the casing in either direction from normal, but resisting return movement of the casing.
2. A spring reaction neutralizer comprising a member adapted to be secured to a vehicle chassis, a casing mounted on said member and having an arm adapted to be connected to the vehicle axle, said member and casing cooperating to define an oil tight chamber, an inelastic fluid in the chamber, a cylinder secured to the casing within said chamber, a spring-actuated control valve at the upper end of the cylinder, a hollow plunger movable in the cylinder and having an intake valve at its lower end, a cam adapted to actuate said plunger when said casing is relatively rotated upon the member, one of said valves permitting unrestricted flow of fluid into said cylinder and plunger, when the casing is rotated in either direction from normal, and the other valve tending to prevent discharge of fluid from said cylinder and plunger to resist return movement of the casing to normal.
3. A spring reaction neutralizer comprising a member having means for securing it to a vehicle chassis, an annular flange on said member, a casing rotatably mounted upon said member and having an arm adapted for connection with the vehicle axle whereby relative movement of the axle will relatively rotate said casing, a fluid chamber defined by said member and casing, an inelastic fluid therein, a cylinder mounted upon said casing within the chamber and having a partially balanced spring-actuated discharge valve at the upper end thereof, a hollow plunger within the cylinder having a head at one end thereof, an intake valve in the plunger adjacent to said head, a cam on said member, a spring constantly holding said plunger head against said cam, said spring causing the plunger to be moved downwardly when said casing is moved in either direction from normal, whereby said intake valve is opened to permit fluid to flow from the chamber into said plunger, return movement of the casing being resisted by the action of said cylinder discharge valve which constantly tends to prevent discharge of fluid from the cylinder as the casing is returned to normal position, such resistive forces substantially neutralizing the reactive forces stored in the vehicle spring with which the device is associated, when the vehicle spring is in abnormal position.
4. A spring reaction neutralizer comprising a member adapted to be secured to a vehicle chassis, a casing on said member having an operative connection with the vehicle axle and cooperating with the member to define an oil tight chamber, an inelastic fluid in said chamber, a cylinder secured to the casing within the chamber, a spring-actuated control valve in the cylinder, a hollow plunger movable in the cylinder and having an intake valve, a cam adapted to actuate said plunger when said casing is relatively rotated upon the member, one of said valves permitting unrestricted flow of fluid into said cylinder and plunger, when the casing is rotated in either direction from normal, and the other valve tending to prevent discharge of fluid from said cylinder and plunger to resist return movement of the casing to normal.
5. A spring reaction neutralizer comprising a member having means for securing it to a vehicle spring, a casing rotatably mounted on said member and having means for connecting it with the vehicle axle whereby relative movement of the axle will relatively rotate said casing, a fluid chamber defined by said member and casing, an inelastic fluid therein, a cylinder mounted on the casing and having a partially balanced spring-actuated discharge valve, a hollow plunger within the cylinder having a head at one end thereof, an intake valve in the plunger adjacent to said head, a cam on said member, means constantly holding said plunger head against said cam, said means causing the plunger to be moved downwardly when said casing is moved in either direction from normal, whereby said intake valve is opened to permit fluid to flow from the chamber into said plunger, return movement of the casing being resisted by the action of said cylinder discharge valve which constantly tends to prevent discharge of fluid from the cylinder as the casing is returned to normal position, such resistive forces substantially neutralizing the reactive forces stored in the vehicle spring when said vehicle spring is in abnormal position.
6. A spring reaction neutralizer comprising a casing having a chamber adapted to contain an inelastic fluid, a cylinder movably mounted with said casing, a spring-actuated control valve at one end of the cylinder, a hollow plunger movable in the cylinder and having an intake valve, a cam adapted to actuate said plunger when said cylinder is relatively moved with the casing, one of said valves permitting unrestricted flow of fluid into said cylinder and plunger, when the casing is moved in either direction from normal, and the other valve tending to prevent discharge of fluid from said cylinder and plunger to resist return movement of the cylinder to normal.
7. A spring reaction neutralizer comprising a casing having a chamber therein adapted to contain an inelastic fluid, a cylinder mounted for movement with said casing, a partially balanced spring-actuated discharge valve at one end of the cylinder, a hollow plunger within the cylinder provided with a head, an intake valve in the plunger adjacent to said head, a cam within the casing, a spring constantly holding said plunger head against said cam, said spring causing the plunger to be moved in one direction when said casing is moved in either direction from normal, whereby said intake valve is opened to permit fluid to flow from the chamber into said plunger, return movement of the casing to normal being resisted by the action of said cylinder discharge valve which constantly tends to prevent discharge of fluid from the cylinder as the casing is returned to normal position.

the casing is returned to normal position, such resistive forces substantially neutralizing the reactive forces stored in the vehicle spring with which the device is associated, when said vehicle 5 spring is in abnormal position.

8. A shock absorber for controlling the movement between relatively movable parts comprising a fluid-containing chamber arranged to be mounted upon one of said parts, a rotatable unit 10 operatively disposed within said chamber, said unit including a hollow sleeve having inlet and outlet ports and a check valve operative associated with the inlet port, an operating arm secured to said rotatable unit and having the free 15 end thereof connected to the other of said relatively movable parts, and means for causing the fluid in said chamber to be drawn into the interior of said hollow sleeve upon movement of said operating arm in one direction, said check valve be-

20

ing operative to restrict the free passage of said fluid from said sleeve upon sudden reverse movement of said operating arm.

9. A shock absorber for vehicle bodies including, in combination, a fluid pressure chamber, a cylinder oscillatably mounted within said chamber, a check valve arranged to permit the passage of fluid from said chamber into said cylinder, the latter being provided with a constricted opening through which the fluid contained therein may be returned into said chamber, means for drawing fluid by way of said check valve into said cylinder upon oscillation of said cylinder in one direction, and means for forcing said fluid out of said cylinder and into said chamber by way of said constricted opening, said last mentioned means being operable upon sudden oscillation of said cylinder in the opposite direction.
